UNITED STATES PATENT OFFICE.

JOHN C. BARBER, OF CHICAGO, ILLINOIS.

CAR-TRUCK.

No. 863,012.

Specification of Letters Patent.

Patented Aug. 13, 1907.

Application filed April 15, 1907. Serial No. 368,172.

To all whom it may concern:

Be it known that I, JOHN C. BARBER, a citizen of the United States, residing at Chicago, in the county of Cook and State of Illinois, have invented certain new and useful Improvements in Car-Trucks; and I do hereby declare the following to be a full, clear, and exact description of the invention, such as will enable others skilled in the art to which it appertains to make and use the same.

- 10 My invention relates to car trucks of the general type disclosed in my numerous prior patents, wherein provision is made for a limited lateral motion of the car body relative to the truck in addition to the customary swiveling motion of said parts.
- 15 More specifically stated, I embody in the present design anti-friction devices adapted to support the car body and its load through the side bearings, with provision for both the lateral and swiveling motions by the use of devices similar in principle to those dis-
- 20 closed and claimed in the Lake and Deverell patent, 798,350, of August 29th, 1905, which patent is owned by the same corporation holding title to my present application and prior patents.

The special object is to provide a truck of this type 25 which shall be well adapted for commercial use and be comparatively simple in construction.

To these ends, my invention consists of the novel devices and combinations of devices hereinafter described and pointed out in the claims.

30 The invention is illustrated in the accompanying drawings, wherein like notations refer to like parts throughout the several views.

Referring to the drawings; Figure 1 is a view chiefly in side elevation, with some parts removed and others shown in diagram only, illustrating a truck equipped with my invention. Fig. 2 is a plan view of the parts shown in Fig. 1, with some portions broken away and other parts removed. Fig. 3 is a detail showing side bearing roller cage detached, in edge view or elevation 40 with respect to Figs. 1 and 2. Fig. 4 is a view, in vertical cross section, through a portion of the truck, with some portions shown in elevation and others broken away. Fig. 5 is a view, in horizontal section, on the line $x^5 x^5$ of Fig. 4. Fig. 6 is a detail, in cross section, 45 through the center plates on the line $x^6 x^6$ of Fig. 5. Fig. 7 is a view chiefly in side elevation, with some parts in vertical section, showing the combined top arch and bolster columns and parts connecting the same with the bottom arch and tie bar. Fig. 8 is a 50 detail, in vertical section, on the line $x^8 x^8$ of Fig. 7. Fig. 9 is a horizontal section on the line $x^9 x^9$ of Fig. 7; and Fig. 10 is a view in section taken on the line $x^{10} x^{10}$ of Fig. 7.

The tie bar 1 and the bottom arch bar or truss bar 2

are of substantially the customary form. The top arch 55 bar 3 and the bolster columns 4 are formed integral with each other. The said top arch bar 3 is widened or expanded laterally, at its central portion, and provided with an opening 5 through which the side bearings can work, as will later more fully appear. The 60 column base 6 is of a shape adapting it to embrace the central or lapping portion of the bars 1 and 2, and to afford means for connecting the said bars to each other and to the columns 4 and to the cross ties 9. Because 65 of its function and shape, the said column base 6 may be called a saddle plate, or be spoken of as of saddle-like form. The columns 4 are of channel box form, as best shown in Figs. 7 to 10 inclusive, and rest with their lower ends or feet upon the horizontal flanges of the saddle plates 6, between vertical lugs 6^a, as best 70 shown in Figs. 8 to 10. Bolts 7 pass through the feet of the columns 4 and through the bars 1 and 2, and bolts 8 pass through the side flanges of the bolster columns 4, and the lugs 6^a rising from the saddle plates 6 with which the feet of the columns telescope, thus securing 75 all the said parts rigidly together.

Angle bar cross ties 9 are seated in the angles between the columns 4 and the saddle plates 6, and are riveted to the tie bars and to lugs 6^b of the saddle plates, as best 80 shown in Figs. 1 and 7 to 10 inclusive, thus serving to reinforce these parts and to connect the bolster columns and the saddle plates of the opposite side frames. By the said parts, marked 6 to 9 inclusive, it is therefore 85 obvious, that the bolster columns 4, the saddle plates 6, the truss bars 2 and the tie bars 1, are all rigidly connected together, and the two side frames of the truck are rigidly connected to each other. The bottom arch bar 2 has its outer ends rigidly connected to the outer ends of the top arch bars 3, as clearly shown in Fig. 1. The side frames are related to the journal boxes of the wheels 90 in the customary way, not shown. The wheel lines 10 are indicated in diagram only in Fig. 1 of the drawings. The combined top arch bars 3 and bolster columns 4 may be of cast steel or pressed steel shaped to the form desired.

Upon suitable seats, afforded by the horizontal webs of the angle bar cross ties 9 and the central portions of the saddle plates 6, are mounted springs 11 upon the upper ends of which rest shimming blocks or caps 12, on which, in turn, is mounted the bolster 13. The 100 bolster 13 is, as shown, composed of an ordinary steel bar laid down flatwise with its heads bearing against the inner faces of the bolster columns 4, and having riveted thereto keeper lugs 14 which embrace the outer sides of the columns 4 and coöperate therewith to afford 105 guides permitting the bolster 13 freedom for up and down motion with the springs 11 but preventing any lateral motion of the bolster crosswise of the truck.

The shimming blocks or caps 12 are shown as riveted to the horizontal web of the bolster 13. The bolster 13 has cast integral therewith, or rigidly secured thereto roller bearing plates 15, located near the ends of the 5 bolster, in position to be directly above the bolster supporting springs. The roller bearing surfaces on the faces of these plates 15 run crosswise of the bolster, and on the same are mounted cylindrical rollers 16. Upon the rollers 16 is mounted a plate 17 which, on account 10 of its function, may be called a floating plate. This plate 17 has roller bearing surfaces on its under side, extending crosswise of the truck bolster and corresponding with the surfaces on the lower bearing plates 15, for coöperation with the rollers 16 located between 15 the said two plates, to permit and secure lateral motion of the car body relative to the truck. The floating plate 17 has a flanged upper face adapted to serve as a bearing surface or tread for side bearing rollers 18 disposed thereon crosswise of the lateral motion rollers 16 20 located between the plates 15 and 17. The body bolster 20 has formed integral therewith or rigidly secured thereto side bearing blocks 19 with flanged under faces running parallel with the flanged upper face of the floating plate 17 and resting on the side bearing rollers 25 18 located between the said parts 17 and 19.

As shown, the side bearing rollers 18 are held in a retaining cage 21, the central cross bar of which is provided with a guide pin 22 projecting above and below the same. The lower end of the guide pin 22 works in 30 a guide groove 23 cut in the floating plate 17 lengthwise of the truck, and the upper end of the guide pin 22 works in a similar groove 24 cut in the side bearing plates 19 lengthwise of the truck. The said cage 21, mounted and guided as described, serves to prevent the 35 bunching of the rollers, and to keep the entire lot of rollers 18 properly centered and positioned in respect to the bearing plates between which they work.

The center plates 25 and 26 are connected in the usual way, one to the truck bolster 13 and the other to the 40 body bolster 20. The said plates 25 and 26 have telescoping or interlocking hubs of unequal size, the hub of the lower plate being considerably larger than the hub of the upper plate, and being also, as shown, of rectangular form, while the hub of the upper plate is of 45 circular form. The two plates 25 and 26 are connected by king pin 27 closely fitted to the hub of the upper plate but working in an elongated slot 28, provided for the purpose, in the lower plate 25. This construction and connection of the two center plates permits the 50 car body and truck to swivel and move laterally in respect to each other, and the vertical end flanges of the lower plate 25 serve to limit the lateral motion. A pair of buffing blocks 29 occupy the space between the engaging hubs of the two center plates at the front and 55 rear of the same, being of segmental form on their inner faces to fit the curvature of the hub of the upper plate, and of straight line form on their outer faces to fit and be guided by the front and rear flanges of the bottom plate 25. The said blocks 29 are of less length than the 60 hub of the lower center plate 25, measured lengthwise of the bolster, the clearance being sufficient to determine the length of the lateral travel; and hence, the said blocks 29 serve to form a close and solid connection between the engaging hubs of the two plates 25 and 26, 65 for taking the forward and backward thrusts, and also

coöperate with the said parts to limit the lateral motion of the car body with respect to the car truck.

The weight of the car body and its load is sustained from the spring supported truck bolster, through said anti-friction devices, marked 15 to 19 inclusive, and 70 which provide for the double motion on rollers, to-wit, the lateral motion of the car body with respect to the truck on the rollers 16, and the swiveling motion of the car body with respect to the truck on the side bearing rollers 18. The floating plate 17 moves with the rollers 75 16, crosswise of the truck, to secure the lateral motion, while the side bearing rollers 18 move on the upper face of said floating plate, lengthwise of the truck or crosswise of the bolster 13. The compounding of the two motions permits the side bearing blocks 19, and the 80 body bolster 20, to move in like arcs of the swiveling circle. As the side bearing rollers 18 are therefore designed to move in the arcs of a circle, they are set on radii of this arc, convergent to the king pin 27 or center of this swiveling motion. 85

The parts are so proportioned that, when in working position, the center plates 25 and 26 do not rest on each other, but are supported apart, with clearance between the two, as clearly shown in Fig. 4. In view of this position of the anti-friction bearing devices, above described, it is, of course, obvious that the load is taken directly over the springs and in the vertical plane of the truck side frames, which is the very best possible place in which to take this strain. It will also be seen that the side bearing members of the anti-friction devices work in and some thereof pass through the openings 5 provided for that purpose in the top arch bars 3 of the side frames. This disposition of these parts enables the truck bolster 13 to work at a lower level than would otherwise be possible, thus bringing the center 90 of gravity of the load lower down on the truck. 95

In virtue of supporting the car body and its load through the side bearings, it is possible to employ a truck bolster and a body bolster of much less weight than is required where the load is sustained from the center plates, thereby greatly reducing the cost of the truck. The forming of the top arch bars 3 and the bolster columns 4 integral with each other affords greater strength than if these parts were made in separate pieces, and enables the said parts to be connected with the bottom arch bars and tie bars through the saddle plates 6 by short bolts 7, instead of the long column bolts usually employed when the columns are made in separate pieces from the top arch bar. This is a simplification effecting considerable economy in the cost of 100 the truck. 110

It will be noted, of course, that the bearing surfaces for the lateral motion rollers 16 are of such a character that the anti-friction devices tend to bring the car body 115 back to central position in respect to the truck, under the effect of gravity. Otherwise stated, the anti-friction devices support the car body with freedom for lateral and swiveling motions when the car is rounding curves, thereby greatly reducing the wear and tear on the wheel flanges and rails and the pulling strain on the locomotive, but permit the car to return to its central position, under the effect of gravity, just as soon as the car again comes on a straight section of track. 120

The efficiency of the anti-friction devices herein disclosed, for sustaining the load through the side bear- 125

ings, with freedom for the motions above noted, has been demonstrated in actual practice.

As shown, the wide portions of the top arch bars 3 have cast integral therewith lugs 30 for supporting 5 brake hangers 31, as best shown in Fig. 10. The fact that the top arch bars are widened out laterally at their central portions enables this direct attachment of the brake hangers thereto, which is a convenience and economy, as compared with the indirect means hitherto 10 employed for the purpose.

What I claim is:

1. In a car truck, the combination with a spring supported truck bolster mounted with freedom for vertical motion but held against any lateral motion crosswise of 15 the truck, of anti-friction bearings supporting the car body from the outer end portions of said truck bolster with freedom for lateral and swiveling motions, and side frame top arch bars having openings through which the said anti-friction devices work, substantially as described.
2. In a car truck, the combination with center plate members connected to permit swiveling and lateral motions of the truck and car body in respect to each other, of 20 buffering blocks filling the spaces between the front and rear sides of the engaged hubs of the center plates to afford a close connection between the said parts for taking the forward and backward thrusts, substantially as described.
3. In a car truck, the combination with anti-friction devices supporting the car body through the side bearings, with freedom for swiveling and lateral motions, of center 25 plate members constructed and connected to permit said motions and provided with buffering blocks filling the spaces between the front and rear sides of the engaged hubs of

said plates to afford a close connection between the said parts for taking the forward and backward thrusts, substantially as described.

35

4. In a car truck, the combination with center plate members connected to permit swiveling and lateral motions of the truck and the car body in respect to each other, which plates have engaged hubs, one of which travels laterally in respect to the other, of buffering blocks filling the 40 spaces between the front and rear sides of the engaged hubs of said plates and move with said laterally traveling hub, whereby said blocks afford a close and solid connection between the said parts, for taking the forward and backward thrusts, and coöperate with said engaged hubs to 45 limit the lateral travel, substantially as described.

5. In a car truck, side frames having their top arch bars and their entire bolster columns formed integral with said top arch bars, having column base plates, of saddle-like form, embracing the bottom arch and tie bars, and rigidly 50 connected to said bars and columns, and having angle bar cross ties connecting the columns and saddle plates of the opposite side frames, substantially as described.

6. The combination with the tie bar 1 and bottom arch bar 2, of the top arch bar 3 and bolster columns 4 formed 55 integral with each other, and the column base 6, of saddle-like form, embracing said bars 1 and 2 and provided with the lugs 6^a spaced apart in pairs to receive between the same the lower end portions of said columns and to afford reinforcing connections for rigidly uniting all of the 60 said parts by bolts and rivets, substantially as described.

In testimony whereof I affix my signature in presence of two witnesses,

JOHN C. BARBER.

Witnesses:
